To all whom it may concern:

Be it known that I, EUGENE CARRAINE, a citizen of the United States, residing in Philadelphia, Pennsylvania, have invented and produced a certain new and original Design 5 for the Border of a Photographic Mat or Mount, of which the following is a specification.

My design for the border of a photographic 10 mat or mount is fully illustrated in the accompanying drawing, the figure of which represents a face view illustrating the design.

A is the quadrangular base, having in each corner a group of scrolls B, each group consisting of two ornamental S-scrolls arranged 15

I claim—

In testimony whereof I have signed my name to this specification in the presence of two subscribing witnesses.
